UNITED STATES PATENT OFFICE.

ISAAC G. STRAUSS, OF MILWAUKEE, WISCONSIN.

DESIGN FOR A KNIT CAP.

Application filed February 27, 1922. Serial No. 908. Term of patent 7 years.

To all whom it may concern:

Be it known that I, ISAAC G. STRAUSS, a citizen of the United States, residing at Milwaukee, in the county of Milwaukee and State of Wisconsin, have invented a new, original, and ornamental Design for Knit Caps, of which the following is a description, reference being had to the accompanying drawing, forming part thereof.

Fig. 1 is a side view, Fig. 2 is a top plan view, and Fig. 3 is a front view of a knit cap, showing my new design.

I claim:

The ornamental design for a knit cap, as shown.

ISAAC G. STRAUSS.

Witnesses:

A. H. BIESEMEIER,
C. H. KEENEY.
